UNITED STATES PATENT OFFICE.

BENJAMIN KOVACS, OF NEW YORK, N. Y.

SAFETY DOOR-LOCK.

1,265,713.

Specification of Letters Patent.

Patented May 7, 1918.

Application filed October 14, 1916, Serial No. 125,625. Renewed March 23, 1918. Serial No. 224,392.

To all whom it may concern:

Be it known that I, BENJAMIN KOVACS, a subject of the King of Hungary, residing at New York, in the county of New York and State of New York, have invented new and useful Improvements in Safety Door-Locks, of which the following is a specification.

This invention relates to improvements in safety locks, and has as its principal object provisions for preventing outsiders from picking, unfastening or opening the lock. The object can be subdivided into minor objects, one of which is the necessity of using two keys for opening the lock.

Another object is the method of turning these keys, and to provide means within the lock so that one of the keys can be changed should it be necessary.

A still further object is to provide a means within the lock for preventing the unlocking of the lock, should one of the keys not be the proper key.

A further object are means for putting on auxiliary covers on fastening screws, to prevent tampering.

These and other objects are attained by the novel construction and combination of parts hereafter described and shown in the accompanying drawings, forming a material part of this specification, and in which:—

Figure 1 shows a view of the outside cover of the lock.

Fig. 2 shows the end view of the section of the lock, through 1—1.

Fig. 3 shows the view of the inside face of the lock.

Fig. 4 shows a perspective view of the means for receiving the bolt of the lock.

Fig. 5 shows a reverse view of the same means.

Fig. 6 shows one of the tumblers within the lock.

Fig. 7 shows the tripping means.

Fig. 8 shows an assembled view of the inside of the lock, with the bolt out.

Fig. 9 shows a section through 9—9 of Fig. 8.

Fig. 10 shows the inside view of the lock with the bolt in.

Fig. 11 shows the protective cover of the guarded key slot.

Fig. 12 shows the protective cover about to be displaced, and

Fig. 13 shows a detail perspective view of the safety attachment on the bolt.

In Fig. 8, is shown the safety locking attachment which is the main feature of this invention. Within the casing 15 of the lock is a bolt 16 which is slidably adjusted by means of a key which passes through slots 60 17 and engages in notches 18 and 19 of said bolt 16 and at the same time releases a tumbler 20 of the tripping means.

Spring 21 will then press tumbler 22 into notch 23. This operation will take place 65 with one turn of the key, but it is evident that the bolt 16 will not be drawn all the way in, therefore, keeping the door still locked.

Another turn of the key will cause projection 22 of the tumbler mechanism to enter slots 24. This will draw the bolt of the lock all the way in, allowing the door to be opened.

When the key, which operates the bolt 16, 75 is turned, the bolt 16 will be drawn in, at the same time, an angular projection 25 which is also attached, as shown, to the bolt is, drawn inwardly. Projection 26 of the said angle piece 25 must be free to slide within 80 the cavity 28, formed by the alinement of a series of grooves in the tumblers 27, otherwise the bolt 16 will be prevented from being drawn within the casing 15.

Therefore to draw in bolt 16, it is necessary to aline the openings 28 of the tumblers 27 so that projection 26 will be free to slide therein. To accomplish this, the four tumblers 27 having slots 28 normally not in the same line, must be lined up in such a 90 manner that the slots 28 of the tumblers are in one line and held that way to allow projection 26 of the bolt 16 to enter freely therein.

These four tumblers are operated from 95 the outside by a key entering through slot 29. This key is so designed as to conform with the shape of the four adjacent tumblers so that when said key is turned, the tumblers will rise and allow the projection 26 to enter 100 the slot 28, so that the bolt 16 may be withdrawn by the turning of the key entered through the key slot 17. These tumblers are pivoted on the pin 30.

In order to operate the lock from within, 105 it is merely necessary to use the key through the slot 17, the tumblers being raised from this side by means of a lever 31, provided with a pin 32, which, extending through slot 33, is adapted to engage the underside of the 110

projections 34 formed on tumblers 27 in such manner as to aline the tumblers to allow the projection 26 to easily enter grooves 28.

On the outside of the lock I prefer to conceal the key slot 29 by means of a plate 35 which is pivoted at one end to the casing, for swinging movement, so as to clear the key slot 29 when access is desired thereto, the opposite end of said plate being designed to be latched in any suitable manner to the casing when the plate is swung into position to conceal the key slot.

In Fig. 11, the plate 35 is shown, covering the key slot 29. It is a normal position and locked. In Figs. 12 and 1, it is shown open by merely pressing button 36 and turning the plate 35 away from the key slot 29 and thereby uncovering the same.

Figs. 4 and 5 show the keeper of the lock 20 with an auxiliary cover 40, which covers up the screws to prevent outsiders from tampering with the screws of the lock. 46 is the screw plate for fastening to the door, 47 is the opening for allowing the bolt to enter 25 the casing 45 when the door is locked.

In Fig. 1, the plate 37 is an auxiliary plate and which is really held on to the main body of the lock by means of screws 38 and screws 39 which are merely decoys. An attempt 30 could not be made to break open the lock by

taking out screws 39, since it is fastened by screws 38 along the edge of the door.

Having thus described my invention, what I claim as new and desire to secure by Letters Patent is:—

In a lock, the combination with a casing and a bolt horizontally slidable therein, said bolt having two spaced notches in its under side adapted to be engaged by a key and also having notches in its top side, of a spring actuated tumbler pivoted to the casing and engageable with the top side notches, means for actuating said tumbler co-incidentally with the sliding of said bolt when the bolt key is manipulated, an offset right-angled element combined with said bolt and a plurality of semi-disk-like tumblers pivoted in such manner as to engage with said bolt and said right-angled element to positively prevent the unlocking movement of the bolt when in locked position, said semi-disk-like tumblers having alined grooves for the suitable reception of the said right-angled member when the bolt is in unlocked position, the said semi-disk-like tumblers being operable by a separate key from the outside of the casing.

In testimony whereof, I have signed my name to this specification.

BENJAMIN KOVACS.
